US0D1069125S

(12) **United States Design Patent** (10) **Patent No.:** **US D1,069,125 S**
(45) **Date of Patent:** **** Apr. 1, 2025**

(54) **INSTRUMENT CART**

- (71) Applicant: **Auris Health, Inc.**, Santa Clara, CA (US)
- (72) Inventors: **Jonathan Mendoza**, San Francisco, CA (US); **Frankie Vazquez**, San Francisco, CA (US); **Toby A. Stopper**, San Francisco, CA (US); **Wonbin Choi**, San Francisco, CA (US)
- (73) Assignee: **Auris Health, Inc.**, Santa Clara, CA (US)

(**) Term: **15 Years**

(21) Appl. No.: **29/876,778**

(22) Filed: **May 27, 2023**

Related U.S. Application Data

- (60) Continuation of application No. 29/808,573, filed on Sep. 21, 2021, now Pat. No. Des. 991,459, which is a division of application No. 29/634,021, filed on Jan. 17, 2018, now Pat. No. Des. 932,628.

(57) **CLAIM**

The ornamental design for an instrument cart, as shown and described.

DESCRIPTION

FIG. 1 is a top, front, left perspective view of an instrument cart;

FIG. 2 is a front view of the instrument cart;

FIG. 3 is a rear view of the instrument cart;

FIG. 4 is a right-side view of the instrument cart;

FIG. 5 is a left-side view of the instrument cart;

FIG. 6 is a top view of the instrument cart; and,

FIG. 7 is a bottom view of the instrument cart.

In the drawings, the broken lines are for the purpose of illustrating portions of the instrument cart, that form no part of the claimed design.

1 Claim, 7 Drawing Sheets
